UNITED STATES PATENT OFFICE.

WILLIAM W. BOOTH, OF TOLEDO, OHIO.

SUPPLEMENTARY HANDLE FOR TOOLS.

1,391,452.

Specification of Letters Patent. Patented Sept. 20, 1921.

Application filed June 1, 1920. Serial No. 385,560.

To all whom it may concern:

Be it known that I, WILLIAM W. BOOTH, a citizen of the United States of America, residing at Toledo, Lucas county, Ohio, have 5 invented new and useful Supplementary Handles for Tools, of which the following is a specification.

This invention relates to features of handles for tools.

10 This invention has utility as a supplementary handle for manually actuated tools driven for rotation by direct pressure, as drills, and more particularly screw drivers.

Referring to the drawings:

15 Figure 1 is a side elevation of an embodiment of the invention in connection with a pressure rotated hand tool, the instance being of an automatic screw driver known as "Yankee";

20 Fig. 2 is a plan view of the transverse bar of grip member of the supplementary handle;

25 Fig. 3 is a perspective view, from the mounting side, of the bar or member of Fig. 2;

30 Fig. 4 is a perspective view of the normal handle embracing ferrule, which serves to bring and hold the bar or member in assembled anchoring position as to the normal handle; and

Fig. 5 is a section of the detachable supplementary handle in assembled position on a tool handle.

In the instance of the "Yankee" automatic 35 screw driver herein shown, there is the rotatably actuated tool 1 detachably held by chuck 2 for rotation with helically grooved stem 3 normally thrust by spring 4 for rotation in moving out of stock 5. This stock

40 5 has fixedly mounted thereon, remote from the screw driving tool 1, a normal handle 6 having a terminal bulge 7 as a grip for usual tool operations.

For rapid and continuous work, especially, with large screws, or in woods offering considerable resistance or friction to setting of the screws, the normal handle is extremely wearing and fatiguing upon the worker, as compared with advantages for

45 50 holding and pressure impelling contributed by the supplementary handle of the invention herein. While in some minor or special work, the normal handle has its place, for which it is well to retain the tool normal handle, as herein provided; the especially arduous duties are very materially eased up

by the supplementary handle of this disclosure. Usual operation, with each handle is by holding against rotation, and applying pressure axially. 60

For lightness, strength, and ready assembly without mutilation of the normal handle, there is disclosed herein an embodiment of the supplementary handle invention comprising a palm seat providing member or transverse bar embodying a cap or top portion 8, opposing which is a second sheet metal portion 9 having brazed joint 10 in assembly with the portion 8 in completing one element and the supplementary handle 70 portion of the device. The under or second portion 9 has centrally protruding therefrom a collar or flange 11 provided with internal threads 13 throughout. About the central, slightly arched portion 13 may be inwardly struck lugs 14. The arched portion 13 on the inner side provides a seat for engaging the terminal of the tool normal handle, and in some instances supplemental lugs 14 may not be necessary to hold the transverse bar 80 8, 9, against rotation as to the handle 6, 7. In the "Yankee" screw driver, the assembly of the spring 4 in the grip 6, 7, results in a terminal screw which is cleared by the lugs 14 being eccentric so such lugs may embed 85 in the wooden bulge 7.

Of a size precluding assembly over the handle 6, 7, toward the tool, there is provided a ferrule 15 having tapered form with an external thread 16, on the enlarged portion running out toward the reduced portion. The reduced portion of this ferrule 15 has provision for ready finger engagement in effecting rotation, herein shown as knurled portion 17. This ferrule 15 is assembled by moving from the tool 1, over the handle 5, to be drawn up on the inner taper of the bulge 7 as the threads 16 coact with the threads 12. There is thus simply accomplished an assembly and simultaneous anchoring with no mutilation, a supplementary handle readily discarded. The palm fitting contour of the transverse bar affords easy mechanical advantage in holding the tool handles against rotation as the pressure 100 impels tool rotation in driving a screw. Furthermore, as the supplementary handle is axially fixed in both directions with the primary handle 6, 7, screw withdrawal may also be brought about in the use of this supplementary handle. 105 110

The current configuration for normal han-

dles as disposed axially of tools, in many instances has not material variation. In fact as between some different sizes of "Yankee" automatic screw drivers, the handle variation is very slight. This means that the running out of the threads on the two members of the supplementary handle, in combination with the reduced end taper of the ferrule, may combine as automatic or self adjusting means in adapting a standard set of ferrule and transverse bar for a range of general application. Such application for use is one requiring no tools, and convenient to any tool user, by running up the ferrule by engaging the knurled portion 17 and holding the bar or member 8, 9. Such assembly, only by hand, is ample to withstand even extended tool use without supplemental tightening. For removal, mere reverse rotation of the ferrule as to the bar brings about severing of the two members.

What is claimed and it is desired to secure by Letters Patent is:

1. A supplementary handle for a tool provided with a coaxial terminally bulged grip, said handle embodying a transverse bar, and a grip engaging ferrule to mount the bar on the grip.

2. A supplementary handle for a tool provided with a coaxial terminally bulged grip, said handle embodying a transverse bar provided with an internally threaded collar,

and a grip engaging externally threaded ferrule to anchor the bar on the grip by threading into the collar of the bar.

35

3. A supplementary handle for a tool provided with a coaxial terminally bulged grip, said handle embodying a transverse bar provided with a protruding internally threaded collar, and a grip engaging ferrule having threads, said ferrule movable along the grip from the tool toward the bulge as the threads of the ferrule coact with the threaded collar of the bar in anchoring the bar to the grip.

40

4. An automatic screw driver provided with a normal terminal pressure applying handle, and a supplementary handle therefor comprising a transverse bar, and means for detachably anchoring the bar to house the pressure applying end of the handle for driving and withdrawal actuations.

45

5. An automatic screw driver provided with a normal handle, and a supplementary handle therefor comprising a sheet metal member having a threaded collar for enveloping the normal handle by assembly thereon remote from the tool toward the tool, and a ferrule mountable upon such normal handle from the opposite direction and engaging the member to anchor the member to the normal handle and thereby assemble the supplementary handle in position.

55

In witness whereof I affix my signature.

WILLIAM W. BOOTH.
